(57) **CLAIM**

The ornamental design for an electronic feeding and sleep system, as shown and described.

DESCRIPTION

FIG. 1 is a perspective view of an electronic feeding and sleep system embodying the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the FIGS. 3–7 are included for the purpose of illustrating portions of the electronic feeding and sleep system that form no part of the claimed design.

1 Claim, 5 Drawing Sheets
